UNITED STATES PATENT OFFICE.

FRANKLIN WESLEY SPRINGER, OF MINNEAPOLIS, MINNESOTA.

ELECTRICAL REGULATING SYSTEM.

Application filed February 15, 1924. Serial No. 693,035.

My invention relates to regulators for alternating current or direct current electric supply or distribution systems and has for its object to provide a device whereby the current or voltage of the system may be regulated or adjusted within the range of the device and be automatically maintained at the desired voltage or current.

Another object of the invention resides in providing a relay for regulating the voltage or current of the system and to provide means operable in conjunction therewith for varying the voltage or current by means of which the relay may be made to function at all times at its maximum efficiency and effectiveness, without precise and troublesome adjustments.

Another object of the invention resides in using in conjunction with said relay means whereby the current or voltage may be quickly varied as required, without changes of the relay.

Another object of the invention is to provide means whereby the character of the delivered current may be changed quickly as desired without disturbing the relay adjustments, which means may be positioned at the switchboard and operated by remote control.

A still further object of the invention resides in providing means whereby a constant current or voltage is delivered to the relay actuating coil from the line to be regulated, fluctuations of which cause the relay to become operated; and in addition to provide means for varying the current or potential of the sources of electric supply, together with means for controlling said regulating means so as to deliver a normally constant voltage or current at the coil of said relay.

The full objects and advantages of my invention will be found in the detailed description thereof and are particularly pointed out in the claims.

In the drawings illustrating my invention in one form:

Figure 1 is a wiring diagram showing my invention applied to a constant voltage, alternating current system.

Figure 2 is a wiring diagram showing the invention applied to a constant current alternating current system.

Figure 3 is a wiring diagram showing my invention applied to a constant voltage, direct current system.

Figure 4 is a wiring diagram showing my

invention applied to a constant current, direct current system.

In the regulation of distribution systems employing a relay for this purpose, it is highly desirable to have the relay operate at the one setting which makes the relay most efficient and effective and produces the best results. When once this setting has been secured it is preferable not to disturb the same. In ordinary systems if this setting does not give the exact degree of regulation desired it becomes necessary to readjust the relay until such a regulation as is desired can be had. It does not always follow that when the desired regulation has been obtained that the relay is operating most effectively and efficiently. With my invention the relay may be set to so operate and the current or voltage thereafter varied to produce the results desired.

My invention is particularly adapted to be used in conjunction with constant voltage, alternating current systems and may be so applied that a number of different voltages may be secured from the system, which are at all times maintained constant.

In the installation shown in Figure 1, I have illustrated a three-phase supply line L^1 , L^2 and L^3 , which may be supplied by any three-phase generator, which is well known in the art and need not be illustrated in this application, and which is adapted to supply a substantially constant voltage varying within fixed limits depending upon the inherent characteristics of the machine, upon fluctuations of the speed and upon fluctuations of the load taken care of by the same. The line L^1 , L^2 , L^3 is connected to a regulating transformer R which in turn is connected to a distribution line D^1 , D^2 and D^3 by means of which the electrical energy may be distributed to the points to which the loads are to be supplied to the system.

The transformer R may be of ordinary construction such as illustrated in the drawing. This transformer consists of three pairs of primary coils A^1 , A^2 , B^1 , B^2 , C^1 and C^2 which may be connected together in series by means of leads 10, shown in full lines. The coils A^1 — A^2 , B^1 — B^2 and C^1 — C^2 are mounted in fixed relation within the transformer R . Adjacent these coils are positioned three additional coils E , F and G which are secured to a shaft 13 and are adapted to be rotated relative to the said fixed coils so that the relative interlinkage

of the lines of force resulting from the field thereof may be varied at will by the rotation of shaft 13 to vary the voltage or current in said fixed coils. Coils E, F and G may be connected together in Y by means of leads 14 shown in Figure 1 or they may be connected in delta if desired. These coils are energized from line L¹, L², L³ by means of a branch line indicated at 16, 17 and 18 to which leads 19, 20 and 21 terminating at these coils are connected.

With this arrangement the coils E, F and G forming the primary of the regulating transformer R are energized, which coils through the inductive properties of the transformer transfer the energy to the coils A, B and C which being connected in the lines L¹, L² and L³ cause the voltage of the same to be increased or decreased depending upon the relative position of shaft 13 and the coils E, F, G to said coils A, B, C. It can readily be seen that by proper positioning of the said shaft that any desired voltage within the range of the device can be produced in line D¹—D²—D³.

For operating the shaft 13 an electric motor M is employed, which is diagrammatically indicated in the figure in which it is illustrated as having a gear 22 attached thereto, which meshes with a gear 23 fast upon the shaft 13. As motor M rotates the relative positions of the primary and secondary coils of transformer R are caused to be varied so that the regulation desired may be obtained.

For starting and stopping the motor M a switch S is employed which has four fixed contacts 24, 25, 26 and 27 and two movable contacts 28 and 29 adapted to make contact therewith. The contacts 28 and 29 are insulated from and attached to two plungers 30 and 31 which are attracted by two magnet coils 32 and 33 associated therewith.

The motor M is illustrated as a three-phase motor. This motor M is connected up to the switch S as follows: Three leads 34, 35 and 36 are shown, of which the leads 34 and 36 are directly connected to the movable contacts 28 and 29. The other lead 35 is directly connected to the lead 17 which is connected to the line L². The other two terminals of the lines 16 and 17 have connected to them two leads 37 and 38. The lead 37 is connected to contact 24 and also to contact 26, while the lead 38 is connected to contact 27 and to contact 25. With this arrangement it can readily be understood that when the plunger 31 is attracted contacts 28 and 29 are caused to come in contact with the contacts 24 and 25, thereby causing the motor M to rotate in one direction, and when the plunger 30 is attracted by the coil 33 the contacts 28 and 29 are caused to come in contact with the contacts 26 and 27, which causes the current in the two

leads 34 and 36 to be reversed and the motor M to travel in the opposite direction. With this arrangement the primary coils of the transformer R may be rotated in either direction to increase or decrease the compensating effect of the secondary coils thereof upon the line L¹, L², L³.

For operating the switch S a relay H is employed. This relay is provided with a switch arm 39 having at one end a plunger 40 adapted to be attracted by a coil 41 and being arranged at its other end to make contact with either of two fixed contacts 42 and 43. The coil 41, as will be presently described, becomes actuated upon fluctuations of the line voltage, causing the arm 39 to make contact with either of the contacts 42 or 43. In conjunction with the contacts 42 and 43 I employ two coils 45 and 46 which have connected in series with them a resistance 47 by means of leads 48 and 49. These coils are further connected by leads 50 and 51 to the coils 32 and 33 of the switch S. In addition, two jumper leads 52 and 53 are employed which are connected to the leads 51 and 50 at their points of contact to coils 45 and 46 and which connect to the fixed contacts 42 and 43. By means of these jumper leads circuits can be made when the arm 39 is operated which shunt these coils and render the same ineffective for the purpose desired. Coils 45 and 46 are adapted to attract the ends of the arm 39 when energized and to thereby prevent the device from chattering and maintain either the contact 42 or 43 closed during the period over which the motor M is operating. A circuit 54—55 connects the arm 39 and an intermediate point on the resistance 47 with the conductors D² and D³ respectively of the main line.

As the relay H is operated the following circuits are completed: When arm 39 makes contact with contact 42 current flows from line D² through circuit 54, arm 39, contact 42, jumper lead 52, lead 51, coil 33, circuit 38, and circuit 16 to L¹. This has the effect of energizing coil 33 which causes the movable contacts 28 and 29 to come in contact with the fixed contacts 27 and 26, thereby causing the motor M to operate and vary the angularity of the movable coils relative to the fixed coils of the transformer R so as to alter the regulation on the line. At the same time a circuit may be traced similarly up through coil 33, through coil 32, back through lead 50, coil 46, lead 49, one-half of resistance 47, lead 55, back to line D³. This circuit, having both coils 32 and 46 in it does not sufficiently energize either of these coils to actuate the same. At the same time a circuit may be traced through line 54, arm 39, contact 42, lead 52, coil 45, line 48, one-half of resistance 47 and line 55, back to line D³. By means of

this circuit coil 45 becomes sufficiently energized so that the arm 39 is attracted thereby and normally maintained closed, thereby preventing chattering of said arm. As soon as the voltage becomes properly regulated arm 39 drops away from contact 42, deenergizing the switch S and breaking the circuit operating motor M, thereby terminating the rotation of the movable coils of the transformer R. In a similar manner when the voltage on the line fluctuates to the other extreme the arm 39 comes in contact with the contact 43 operating switch S in the reverse direction to cause the motor M to travel in the opposite direction, which again changes the angular position of the coils of transformer R, thereby altering the regulation to the required amount.

For energizing the coil 41 of relay H I employ a circuit 56-57 which is also connected to a compensating resistance 58. This compensating resistance is connected by means of a circuit 59-60 to the secondary 61 of a transformer 62. The primary 63 of transformer 62 is connected by means of a line 64-65 with two current transformers 66-67 which are adapted to be operated in conjunction with the two lines D¹ and D³ and which are connected in parallel in the circuit 64-65.

In addition to the foregoing the line 56 is directly connected to a portion of an auto transformer 68 which is provided with a number of taps 69 and 70 adapted to make contact with two swinging arms 71 and 72.

These arms are connected by means of a line 73-74 to a transformer 75 which in turn is connected by a line 76-77 to the lines D² and D³ previously referred to. By this means the voltage on the line operating through transformer 68 tends to vary the current through the coil 41 which varies the pull upon the plunger 40, thereby actuating arm 39 as previously described to control motor M. In addition, the two current transformers 66 and 67 operating in conjunction with the transformer 62 and the compensating resistance 58 serve to modify the current passing through the coil 41 in proportion to the load carried by the line D¹-D²-D³. If desired, the transformer 75 may be embodied in the transformer 68 by the proper design and selection of the taps thereof.

In my invention the taps 69 may be arranged so as to include ten times as many turns as the taps 70, whereby any desired number of turns of transformer 68 may be included between the arms 71 and 72. By this means a substantially constant voltage may be maintained across the portion of the transformer 68 included in line 56, indicated at 78, regardless of the voltage of the line D¹-D²-D³.

In the operation of the invention the re-

lay H is first adjusted to secure the best and most effective operating results by the adjustment of the contacts 42 and 43 relative to arm 39 and the other variable elements of the same. After this has been attained by selection of the proper transformer 75 and by the manipulation of the respective arms 71 and 72 any desired voltage can be secured at the end of lines D¹-D²-D³. This is effected as follows: If the arms 71 and 72 are set for a particular voltage less than that secured by L¹-L²-L³, the voltage across the portion 78 of transformer 68 becomes considerably less than normal and the arm 39 drops making contact with contact 43. This, as previously described, operates motor M to rotate the rotatable coils of transformer R until a bucking effect is produced upon the line D¹-D²-D³ which is sufficient to bring the voltage down to the required amount. As soon as the voltage across the portion 78 of transformer 68 resumes the normal operating voltage then the arm 39 immediately resumes its neutral and normal position. Any fluctuation in the voltage delivered to the line D¹-D²-D³ immediately operates relay H in the same manner as when the voltage supplied to these lines is the same as that received from the lines L¹-L²-L³. If, on the other hand, a higher voltage than that normally supplied from the line L¹-L²-L³ is desired, arms 71 and 72 are set accordingly and the reverse action takes place.

It will always be noted that the device comes to rest when the voltage across the portion 78 of coil 68 becomes normal and that by the proper adjusting of the arms 71 and 72 any desired voltage within the range of the equipment can be had at the ends of these lines, which is further maintained constant by the regulating means and which may also be compensated for as the load is impressed upon the same.

In Figure 2 I have shown a system similar to Figure 1 which, however, is used for maintaining in an alternating current system a constant current instead of a constant voltage as in Figure 1. I have here shown an alternator 79 having an armature 80 connected with a line 81-82 and a field coil 83 connected to an excitor 84 by means of a line 85. In the excitor circuit 85 is interposed a resistance 86 which is connected by a circuit 87 to the armature 88 of a relay 89. The relay 89, if desired, may be of the vibrating type which is adapted to rapidly open and close the circuit 87 and to cut in and out the resistance 86 so as to vary the exciting current to the field coil 83. The relay 89 is controlled by its coil 90 which is connected in a circuit 91 operated through a current transformer 92 which is also connected in the line 82. It will be

noted that a variable connection indicated at 93 is made with the current transformer 92 to the circuit 91 so that the number of turns of said current transformer included in this circuit may be varied at will. As the current in the system varies the action of coil 90 upon armature 88 is varied to secure the proper exciting current in the field coil 83 of generator 79, thereby maintaining a constant current in the line 81-82. When it is desired to alter the current in this line the movable or variable contact 93 is shifted. This has the effect of changing the current in the coil 90 which acts upon relay 89 to vary the current in the line 81-82 until the current in line 91 again resumes normal. With this device the same as with that shown in Figure 1, the relay 89 is adjusted to function in the most satisfactory manner, after which the percentage of regulation or the exact current desired may be had by simply varying the taps or the movable contact to the current transformer 92.

25 In Figure 3 I have illustrated a constant voltage system similar to that shown in Figure 1 for a direct current system. I here employ a line 94-95 connected to the armature 96 of a direct current generator 97. The field coil 98 of this generator is also connected across the line 94-95 but has connected in series with it a resistance 99. This resistance is adapted to be shunted by a circuit 100 which connects with the armature 101 of a relay 102 similar to relay 89. The coil 103 of this relay is connected in a circuit 104 which has a movable contact 105 adapted to make contact with a resistance 106 which resistance is connected across the line 94-95 and to the other end of the line 104. As the voltage of line 94-95 varies the current in line 104 varies the same as the current in line 91, thereby actuating relay 102 to cut in and out resistance 99 and so regulate the voltage of the line. Relay 102 is again adjusted to the most satisfactory operating position, after which the regulation is secured by varying the contact 105.

50 As can readily be comprehended, my invention may also be used in conjunction with a constant current, direct current system, such an installation being illustrated in Figure 4. In this case a resistance 107 is employed instead of resistance 106, which is connected in series in the line 94 instead of across it. As the current through the portion of resistance 107 cut in by contact 105 varies, the current through coil 103 varies in like manner, and the same regulating effect is produced as with any other formation of the invention.

55 My invention is highly advantageous in that a system may be produced from which any desirable constant voltage or current may be secured which may at all times be

maintained constant regardless of fluctuations of the source of electric supply and the load conditions imparted upon the system. The system provided an installation whereby the regulating relay may be operated at all times at its most efficient and satisfactory operating adjustment so that different currents or voltages may be quickly and positively secured without meddling or interfering with the adjustment of the relay. 75 This insures positive operation and regulation at all times with selectivity of voltages or currents without loss of time or annoyance. It may be further stated that my invention may be positioned upon the switch-board or in close proximity with the devices with which it is associated and the same operated by remote control. 80

In accordance with the patent statutes I have described my invention, illustrating the best embodiment thereof, but I desire to have it understood that the invention can be carried out by other means and applied to uses other than those above set forth within the scope of the following claims. 90

I claim:

1. In combination with an electric supply line for alternating current, means for altering the voltage thereof including a relay, a circuit for operating said relay, a voltage transformer energized from said line and feeding said circuit, means connected in said circuit for compensating for line load, a variable transformer connected in said circuit and a current transformer connected in said line and to said compensating means. 100

2. In combination with an electrical supply line for alternating current, means for altering the voltage thereof including a relay, a circuit for operating said relay, a variable transformer having a portion of the windings thereof connected in said circuit, a second circuit, a potential transformer connected across said line and in said second circuit, the variable windings of said variable transformer being connected in said second circuit, and a current transformer connected in said line and to said first named circuit. 110

3. In combination with an electrical supply line for alternating current, means for altering the voltage thereof including a relay, a circuit for operating said relay, a variable transformer having a portion of one of the windings thereof connected in series in said circuit, a second circuit, a potential transformer connected across said line and in said second circuit, the variable windings of said variable transformer being connected in said second circuit, a current transformer connected in said line and compensating means connected across said current transformer and in said first named circuit. 120

4. In combination with an electrical supply line for alternating current, means for alter- 130

- ing the voltage thereof including a relay, a circuit for operating said relay, a variable transformer having a variable primary and a fixed secondary, the secondary thereof being connected in said circuit and the primary thereof being energized from said line.
5. In combination with an electrical supply line for alternating current, means for altering the voltage thereof including a relay, a circuit for operating said relay, and a variable potential transformer connected in said circuit and across said line.
6. In combination with an electrical supply line for alternating current, a regulating transformer connected thereto having a movable coil, means for operating said movable coil, a relay for controlling said operating means, a circuit for operating said relay energized from said line, an auto transformer having some of the turns thereof connected in said circuit, a number of taps formed on other of said turns and means for adjustably connecting any of said transformer taps with said line.
- 25 7. In combination with an electrical supply line for alternating current, a regulating transformer connected thereto having a movable coil, means for operating said movable coil, a relay for controlling said operating means, a circuit for operating said relay energized from said line, a transformer connected in said circuit and energized from said line and means for adjusting the ratio of the primary and secondary of said transformer to adjust the action of said relay
- upon said movable coil controlling means of said regulating transformer.
8. In combination with an electrical supply line for alternating current, means for altering the voltage thereof, including a relay, a circuit for operating said relay energized from said line, an auto transformer having some of the turns thereof connected to said circuit, a number of taps arranged on other of the turns of said transformer, and means for adjustably connecting any of said taps with said line.
- 40 9. In combination with an electrical supply line for alternating current, means for altering the voltage thereof including a relay, a circuit for operating said relay, a voltage transformer, a circuit connected across said line containing the primary of said voltage transformer, a variable transformer, a circuit containing the primary of said variable transformer and the secondary of said voltage transformer, the secondary of said variable transformer being connected in said relay circuit, a current transformer connected in said line, and means connected in 50 said relay circuit and to said current transformer for compensating for line load.
- 55 10. In combination with an electrical supply line for alternating current, means for altering the voltage thereof including a relay adapted to operate at a fixed voltage, a circuit for operating said relay, and a variable potential transformer connected in said circuit and across said line.

FRANKLIN WESLEY SPRINGER.
